FORM ROLLER AND CYLINDER TRIPPING
MECHANISM

Henri E. Peyrebrune, River Forest, Ill., assignor
to Miehle Printing Press & Manufacturing
Company, Chicago, Ill., a corporation of Delaware

Application May 16, 1950, Serial No. 162,227

2 Claims. (Cl. 101—247)

1

This invention relates to cylinder printing presses. More specifically it pertains to improved mechanism for tripping one of the associated cylinders of a printing couple away from the other and for subsequently tripping the form inking rollers from the printing form.

The improvements which are involved in the invention reduce to a very appreciable degree the heretofore ever present and difficult problem of eliminating roller and gear streaks which frequently develop and which are detrimental to the printed product.

With a view to producing this result, I have developed novel means for maintaining a constant and perfect meshing relation of the form roller driving gears during said tripping of the form rollers. The improvements also include mechanism whereby the established roller setting, i. e. the correct rolling contact relation between the form rollers and the printing form is maintained during said tripping movements.

With these accomplishments in view, it is one of the primary objects of my invention to provide simple and efficient means whereby during the tripping movement of the form cylinder away from its associated cylinder in unison with the form inking rollers, the predetermined contact relation, i. e. setting of these rollers with the form is maintained, and whereby the meshing relation of the main inking roller drive gear with the form cylinder drive gear remains undisturbed.

Another object of the invention resides in the provision of improved mechanism which includes a manually and automatically operable eccentric member having its center of rotation so located with relation to the form cylinder that the movement of the latter toward and away from the impression cylinder occurs in a direction angular to, i. e. intercepts the plane which passes through the axes of the form and impression cylinders.

A further object resides in the provision of novel tripping mechanism which includes means whereby the form rollers may be set manually to remain in contact with the form cylinder when it is in its printing position as well as when it is tripped, and whereby these rollers may be set to remain tripped off said cylinder in both its positions.

A still further object is to provide improved means for automatically tripping the form rollers off the form cylinder when it is in its tripped position.

Other objects and improvements which my invention provides will be apparent from the fol-

2

lowing description and appended claims when read in conjunction with the accompanying drawings.

It will be understood, that the invention is susceptible to the embodiment of various constructional modifications, therefore the disclosure herein is merely by way of example, describing and illustrating a preferred arrangement of the parts involved.

10. In the drawings:

Figure 1 is as side elevational view showing the printing couple of a rotary printing press with the form cylinder, the impression cylinder, the associated form rollers and the tripping mechanism in position for printing;

Figure 2 is a view similar to Figure 1, but showing the form cylinder in its tripped or non-printing position;

20. Figure 3 illustrates the form rollers in their tripped position, i. e. spaced from the form cylinder;

Figure 4 shows a portion of the cylinder tripping mechanism and illustrates the manner in which the tripping pawl is positively controlled 25 while moving from one position to another with its actuating lever;

Figure 5 is a cross sectional view taken along an imaginary line through the inking roller unit for the purpose of showing the manner in which the form rollers and their auxiliary frame members are adjustably supported on the press side frames; and

30. Figure 6 is a cross sectional view on an enlarged scale, taken on line VI—VI of Figure 1.

Referring now to Figure 1 of the drawings, the impression cylinder 10, indicated in broken lines, is journaled for rotation in the side frame members 11 and revolves in counterclockwise direction.

40. A form cylinder 12, which carries the printing plate or form, is arranged preferably above the impression cylinder and is also supported in journals provided in the side frame members 11 at each side of the press. While only one side of the press is shown, it will be understood that many parts described and illustrated herein as applied to that side, will be duplicated on the opposite side thereof.

For the purpose of tripping the form cylinder 12 with respect to the impression cylinder 10 when the printing operation is interrupted, the form cylinder journals are supported in eccentric bores 13 formed in housings 14 which are rotatably mounted in the frame members 11. As a result, when the housings 14 are rotated

50. 55. through a prescribed angle, the eccentricity of

the bore 13 will cause the form cylinder 12 to move away from the impression cylinder 10.

In order to rotate the housings 14 through such a prescribed angle, they are provided with yokes 16 which are securely clamped thereon and are connected to a lever 17 by means of the adjustable toggle link 18. Lever 17 is pivotally mounted on a stud 19 and its free end 21 is connected by means of the rod 22 to lever 23 which is loosely mounted on shaft 24. The free end 28 of lever 23 carries a pawl 27 which is pivotally connected thereto and is provided with operative ends 28 and 29. This pawl is also provided with cam rollers 31 and 32 which are positioned near the ends 28 and 29 respectively and are arranged to cooperate with a fixed cam 33 to control the position of pawl 27. Cam 33 is supported on shaft 24 and is secured in a predetermined position by means of a bolt 34.

A pawl actuating tripping lever 36 is also mounted to rock on the shaft 24 and carries at one end a cam follower 37 which traverses the counterclockwise rotating cam 38 which is mounted to rotate with the impression cylinder 10. The opposite end of lever 36 is provided with opposed jaw faces 39 and 41 which coact with the respective pawl ends 28 and 29 to effect the tripping and return movements of the form cylinder.

The lever 36 is also provided with an arm 42 which carries the cam roller 43 in a position wherein it will ride on cam 44 which is also mounted to rotate with the impression cylinder 10. As a result, the jaw faces 39 and 41 will oscillate constantly about the axis of shaft 24 due to the action of the levers 36 and 42 as their associated cam followers 37 and 43 ride on the conjugate cams 38 and 44.

Pivotally connected to the lower end of pawl 27 is the rod 46, the free end of which is slidably inserted in the pivoted boss 47 and on which is mounted the compression spring 48. Spring 48 exerts a constant pressure against the pawl 27 urging it in a counterclockwise direction.

Under normal operating conditions however, the roller 32 on the pawl 27 is maintained in contact with the cam 33 against the pressure of spring 48 by the cam shoe 49. This shoe is rockably mounted on the stud shaft 51 and is provided with an arcuate roller engaging face 52 which cooperates with the roller 32 to maintain the pawl 27 in the position shown in Figure 1. The shoe 49 is urged against the roller 32 under the resilient pressure of the spring 53 which is mounted on rod 54. The latter passes through a bore provided in the pivoted boss 56 which is arranged on said shoe. This rod is connected to a lever 57 associated with the manual control lever 58. These levers 57 and 58 are in turn mounted to rotate on stud 59. By moving the lever 58 in the clockwise direction when the press is in operation the spring 53 will become compressed so that the face 52 of the cam shoe 49 will urge the roller 32 into contact with the fixed cam 33 against the pressure of spring 48 and thereby the end 29 of pawl 27 will assume the position as shown in Figure 1.

The position of shoe 49 is also controlled by automatic means, not shown, but which are connected to the rod 61. The automatic means may be of any conventional type such as, for example, the mechanism disclosed in the Jacobson Patent #2,100,852 and since it forms no part of this invention it has not been illustrated.

Under normal operating conditions the trip-

ping mechanism will remain in the positions shown in Figure 1 and the jaws 39 and 41 will oscillate about the shaft 24 without affecting the position of the pawl 27. However, when the press is tripped, either manually or automatically for some reason, the following action takes place:

The lever 58 is moved counterclockwise thereby releasing the pressure of spring 53 on the boss 56 as the collar 62 engages said boss to depress the shoe 49, as shown in Figure 2. The pressure of spring 48 then urges the pawl 27 in counterclockwise direction until roller 31 engages the high part of cam 33 so that both ends 28 and 29 of the pawl are engaged by their respective coacting jaws 39 and 41 of the trip lever 36 and as shown in Figure 4.

With the pawl 27 so positioned it will move with the trip lever 36 as it rocks clockwise about the shaft 24 by virtue of the cams 38 and 44 acting against the followers 37 and 43 and both ends of the pawl will remain engaged with the jaw faces 39 and 41 until lever 16 reaches the end of its stroke. Consequently, the movement of the pawl 27 is under positive control of the lever 36 during the tripping and return functions of the mechanism, thereby avoiding any possible overthrow of the associated levers. As a result, the action is smooth and free of shocks and strains which are otherwise present when rigid stops are used to control such mechanism.

As the lever 36 reaches the end of its clockwise stroke, roller 31 drops to the low part of cam 33, due to the pressure of spring 48, thereby causing pawl 27 to pivot counterclockwise until its end 29 is completely free of the jaw face 41, as shown in Figure 2. At this point, lever 36 reverses its direction but pawl 27 will remain motionless until lever 58 is reset, and the end 29 of pawl 27 is again urged into contact with the jaw face 41.

As pawl 27 and therewith lever 26 move clockwise, a corresponding movement is imparted to the arm 23 and thereby to lever 21 and lever 17 through the connecting rod 22. This movement is transmitted through the toggle link 18 to the yoke 16 which rotates the housing 14 through a predetermined angular displacement as shown in Figure 2. Due to the eccentricity of the bore 13 in the housing 14 and in which the form cylinder 12 is journaled, this rotation of the housing 14 causes the form cylinder 12 to move away from the impression cylinder 10 at an angle with respect to a plane which passes through the axes of the two cylinders.

To insure uniform distribution of the ink on the form when the form cylinder is tripped and to thereby avoid streaks on the finished prints, the form inking roller units are raised in unison with the form cylinder in order to maintain the contact relation of the form rollers constant with respect to the form cylinder. The inking roller unit comprises form rollers 63, 64, 66 and 67, which, along with their associated distributor rollers 68 and 69, ink distributing drum 70 and rider rollers 71 and 72, are supported in auxiliary frames 73 and 74 respectively which are movably arranged on the frame members 11. The gibs 76 and 77, bars 78 and 79 and the guide rails 81 and 82 all cooperate to maintain the frame members 73 and 74 in position on the frame members 11 and are arranged to permit raising and lowering of the frames 73 and 74 as they move up and down with the form cylinder.

In the interest of simplicity, the driving gears for the inking rollers have not been shown in the drawings, however it will be readily understood that the inking rollers are driven in a conventional manner from the form cylinder gear and that the axis of the main inking roller drive gear is located in line with a plane drawn thru the axis of the housing 14 and the axis of the eccentric bore 13 so that raising of the form cylinder gear with the form cylinder will not disturb the meshing relation of the two gears.

As shown in Figures 1, 2, 3 and 5 the auxiliary frames 73 and 74 are provided with rollers 83, 84, 86 and 87 which are arranged to ride on the cam 88 forming an integral part of the yoke 16. Consequently, when the yoke 16 is moved in order to separate the form cylinder 12 from the impression cylinder 10, the cam effects a relative raising of the frames 73 and 74 and therewith the form rollers 63, 64, 66 and 67 for the purpose of maintaining the contact relation of said rollers with said form undisturbed.

As is more clearly illustrated in Figure 5, the cam rollers 83, 84, 86 and 87 are mounted on the frame members 73 and 74 with eccentric studs 89 to provide adjustment whereby the cam rollers can be positioned with relation to the cam 88 after the form rollers are set with relation to the form cylinder. This adjustment is necessary to compensate for variations in roller diameters, wear etc.

During the raising movement of the frame members 73 and 74, see Figures 1 and 2, they are guided by rails 81 and 82 respectively which rails are fixed to the main frame members 11 and fit into grooves provided therefor in the auxiliary frame members 73 and 74. The rails 81 and 82 are so designed and located that said movement of the frame members 73 and 74 will not affect the meshing relation of the associated ink roller driving gears and the angular displacement of the form cylinder, due to the eccentricity of the bore 13, will be compensated for.

To provide for adjustment of the contact relation of the individual form rollers with the form cylinder, they are mounted in sockets 91, 92, 93 and 94 formed on the arms 96, 97, 98 and 99 which are adjustably supported on their respective frames 73 and 74. At their bases the arms are held slidably in position, along with the frame members 73 and 74, by means of the bars 78 and 79 which are fixed in position on the frame 11. See Figures 1 and 5. The upper ends of said arms embrace the eccentrics 101, 102, 103 and 104 which are formed on the ends of shafts such as 106, which project through openings in frame member 11 and are provided with manually controlled handles 107 whereby the position of the eccentrics can be adjusted to vary the contact relation of the form rollers on the form cylinder. These eccentrics 101, 102, 103 and 104 are also actuated by automatic means through levers such as 108 to effect tripping of the form rollers off the form cylinder. For a detailed explanation of the form roller setting and tripping mechanism I refer to my copending application Serial #749,803 which is specifically directed to those features.

The position of the form rollers with respect to their associated distributor rollers 68 and 69 is also adjustably maintained. Links 109, 111, 112 and 113 are pivotally connected to their respective arms 96, 97, 98 and 99 with their free ends fitted over the eccentrics 114, 116, 117 and

118. These eccentrics are also formed on the ends of shafts such as 119, in Figure 5, which project through openings in the frame members 11 and are provided with manual controls 121 for adjustment purposes. It will be noted that the openings in the frame members 11, for the shafts 106 and 119, are sufficiently large to permit free up and down movement of said shafts as they move with the auxiliary frames 73 and 74 when the form cylinder is raised and lowered.

After the form cylinder and therewith the form inking units are raised in unison off the impression cylinder, the form rollers 63, 64, 66 and 67 are then tripped off the form cylinder 12 in sequence and in pairs as shown in Figure 3. This tripping action can be accomplished either manually or automatically and the mechanism involved is illustrated and explained in my said copending application. Therefore, I do not deem it necessary to disclose or explain this mechanism in detail in this application.

However, the form roller tripping mechanism referred to is actuated through the lever 122 which is fixed to shaft 123 and can be set for either manual or automatic operation. See Figures 1, 2 and 6. Operating in conjunction with lever 122 is the lever 124 which is loosely mounted on shaft 123 and is provided with an arm 126 which is connected to lever 17 by means of the rod 127. As a result each time lever 17 is actuated by the form cylinder tripping mechanism a relative rocking motion is transmitted to lever 124.

The free end of lever 124 is provided with a recess 128 to receive the pin 129 slidably mounted in lever 122 and which is urged into engagement with lever 124 by the spring 131 acting against flange 132 on the plunger 133. The opposite end of plunger 133 is provided with a knob 134 by which the position of the pin 129 can be changed. As shown in Figure 6 the lever 122 is set for automatic operation with the pin 129 set in the lever 124. Consequently, each time the lever 124 is rocked clockwise, due to its connection with lever 17, the lever 122 will move therewith, turning the shaft 123 and thereby setting up the associated form roller tripping mechanism to move the form rollers off the form cylinder.

To set the lever 122 for manual operation, knob 134 is pulled out until pin 136 is free of the slot 137 and pin 129 is withdrawn from lever 124. Then said knob is rotated through 180° until pin 136 is again in line with slot 137 and pin 129 coincides with the flange 138 on the frame 11. With the pin 129 in this position, movement of lever 124 will not affect lever 122 or shaft 123.

When set for manual operation, lever 122 is moved until pin 129 enters either groove 139 or groove 141, which are marked "On" and "Off" respectively. If pin 129 is set in the "on" position the form rollers will remain in contact with the form cylinder when it is in its printing position as well as when it is tripped, and if set in the "off" position said rollers will remain tripped off the form cylinder in both said positions.

While I have herein disclosed a preferred embodiment of my invention, I do not wish to be limited to specific details because modification in the design and arrangement of parts may be made without departing from the spirit of my invention and the scope of the appended claims.

What I claim is:

1. In a printing press having coacting form and impression cylinders, eccentric journalling means for tripping said form cylinder bodily in a curvilinear path with respect to the impression cylinder, and a main ink drum having rotation about a fixed axis, the combination of, an ink distributing unit for transferring ink from the main ink drum to the printing surface of the form cylinder, said unit comprising a rider roller having contact relation with the main ink drum to receive ink therefrom, form rollers having contact relation with the printing surface of the form cylinder to deposit a film of ink thereon, and a distributor roller arranged to transfer ink from said rider roller to said form rollers, auxiliary frame members for supporting said rider, distributor and form rollers for bodily movement as a unit, means interconnecting said eccentric journalling means with said frame members whereby relative motion in a predetermined path is imparted to said frame members and said rollers as a unit in unison with the form cylinder when the latter is tripped on and off impression, and stationary guide means having sliding engagement with the auxiliary frame members for controlling the angular relation between said frame members and the printing surface of said form cylinder to thereby maintain constant the contact relation of the rider and form rollers with the main ink drum and the form cylinder respectively for all positions of said cylinder.

2. In a rotary printing press having an impression cylinder, a printing form cylinder, means for tripping said form cylinder with respect to said impression cylinder, and an inking roller assembly comprising a plurality of form rollers, a distributor roller, and a rider roller for apply-

5

10

20

ing a film of ink onto the printing surface of said form cylinder, the combination of movable frame members for supporting the rollers of said assembly for bodily movement as a unit, means including a cam adapted to move with said tripping means and coacting cam rollers mounted on said frame member for effecting relative movement of said inking roller assembly in unison with said form cylinder when the latter is tripped, stationary guide means having sliding engagement with said frame members for guiding said frame members and thereby said inking rollers in a predetermined path during said movement to thereby maintain constant the rolling contact relation between the form rollers and the form cylinder, and additional means carried by said frame members and including rotatable eccentric members having a connection with said tripping means and with said form rollers for tripping the form rollers of said assembly off said form cylinder after the latter is tripped.

HENRI E. PEYREBRUNE.
